UNITED STATES PATENT OFFICE.

ADOLPH L. DE LEEUW, OF HAMILTON, OHIO, ASSIGNOR TO THE NILES
TOOL WORKS COMPANY, OF HAMILTON, OHIO.

ELECTRIC SWITCH SYSTEM.

SPECIFICATION forming part of Letters Patent No. 721,942, dated March 3, 1903.

Application filed November 24, 1902. Serial No. 132,553. (No model.)

To all whom it may concern:

Be it known that I, ADOLPH L. DE LEEUW, a citizen of the United States, residing in Hamilton, Butler county, Ohio, have invented 5
certain new and useful Improvements in Electric Switch Systems, of which the following is a specification.

In the controlling of machines cases arise in which an effect is to be produced when 10 some part is in a certain one of several conditions or positions, or as an alternative when the part is in another condition or position, or again when the part is in either of several conditions or positions. A specific example 15 may be found in metal-planing machines in which feeding motion is to be given to the tool for each working stroke of the table, the feeding of the tool to take place not during but between the strokes of the table. It is 20 desirable to have the machine provided with controlling devices, by means of which the operator can selectively determine that the feeding motion shall take place prior to the beginning of the cutting stroke or after the 25 beginning of the cutting stroke, or both prior to and after the cutting stroke.

My invention pertains to an electric switch adapted for such selective control of machinery, and in exemplifying my invention 30 I will assume it as being employed in connection with a metal-planing machine for the purpose of controlling the time when the feeding motion is to take place relative to the strokes of the table.

35 My invention will be readily understood from the following description, taken in connection with the accompanying drawings, in which—

Figure 1 is a diagram illustrating an exemplification of the system, and Fig. 2 a front elevation of the exemplifying construction.

In the drawings, but giving attention exclusively to Fig. 1, 1 indicates a switch-arm, shown in its leftward position, but having also 45 a position to the right; 2, a connection from this switch-arm to some part of the machine in connection with which the device is to be employed, this connection leading in the assumed case of a metal-planing machine to 50 any moving part of the reversing gear of the planer, so that when the table is moving in one

direction the switch-arm 1 will be to the left and when the table is moving in the other direction the switch-arm will be to the right, the switch-arm thus moving from one position to 55 the other while the table motion is being reversed; 3, a connection from the machine to serve, as this connection is shifted, to cause some desired effect to be produced upon the machine—for instance, to cause the feeding 60 of the tool to take place in a metal-planing machine, in which case the connection 3 will have suitable connection with the feed-works of the planer, as by being connected with the latch, which when released permits a feed- 65 cránk to make a turn; 4, a solenoid; 5, its core, having the connection 3 attached to it, so that the inward movement of the core produces the effective movement of the connection 3; 6, a contact-segment engaged by 70 switch-arm 1 at all times; 7, a contact-segment engaged by switch-arm 1 when the switch-arm is to the right; 8, a contact-segment engaged by the switch-arm 1 when the switch-arm is to the left; 9, a hand-switch; 75 10, a contact for switch 9; 11, an alternative contact for switch 9; 12, a second hand-switch; 13, a contact for switch 12; 14, an alternative contact for switch 12; 15, a second switch-arm; 16, a contact-segment for switch-arm 80 15 of such length that the switch-arm may pass beyond each of its ends as the switch-arm makes its complete movement; 17, a second similar contact-segment for switch-arm 15, the switch-arm in passing over the seg- 85 ments serving to bridge between them; 18, a second solenoid; 19, its core, connected with switch-arm 15 and serving when the solenoid is energized to move the switch-arm to its upper position, the gravity of the switch-arm 90 and core serving in the present case to carry the switch-arm to its lower position, it being understood that both the upper and lower positions of this switch-arm are idle or inactive ones; 20, one of the mains leading from any 95 suitable source of current and going to contact 14; 21, the other main, going to contact-segments 17 and to solenoid 18; 22 to 29, inclusive, electrical connections between the parts heretofore referred to, and 30 a vent-hole in 100 the inclosed end of the bore of solenoid 18, of such restricted size as to retard the inflow

and outflow of air to the bore as the core reciprocates therein, and thus serve in retarding the motion of the core.

In the assumed case of a metal-planing machine it is to be understood, then, that switch-arm 1 takes position to the left when the table motion is reversed for the beginning of the cutting stroke and that it takes position to the right when the table motion is reversed for the beginning of the backing stroke. It is furthermore to be understood that if connection 3 be for an instant shifted to the left it will bring about a feeding impulse of the planer. It may be desired that this feeding impulse shall take place only when switch-arm 1 goes to the left—that is to say, just prior to the beginning of the cutting stroke. Again, it may be desired that this feeding impulse shall take place only when the switch-arm goes to the right—that is to say, just prior to the beginning of the backing stroke of the table. Again, it may be desired that feeding impulse shall take place at both the beginning and the end of the cutting stroke.

Hand-switch 12 determines by its position whether the feeding impulse shall take place at one end only of the cutting stroke or at both ends; and hand-switch 9 determines by its position at which end of the cutting stroke the feeding impulse shall take place if it is to occur at one end only of the cutting stroke. As the parts are shown in Fig. 1 the switches are set to bring about a feeding impulse as a result of the movement of connection 3 only at the beginning of the cutting stroke, or when switch-arm 1 goes to the left.

Starting with main 20 and tracing the circuit through its route through 22 9 23 8 1 6 25 46 13 12 29 4 28 16 17 to main 21 we find that this circuit includes solenoid 4, but that it is open at segments 16 and 17, the solenoid being therefore inert; but tracing from main 20 through route 22 9 23 8 1 6 25 26 18 27 to main 45 21 we find that solenoid 18 is energized. The result will be that switch-arm 15 will be raised to its upper position, which, like its lower position, is an inactive one, but in passing upward over segments 16 and 17 it temporarily 50 closed the circuit through solenoid 4, the result being that the solenoid became temporarily energized and connection 3 given an excursion, resulting in a feeding impulse for the assumed planing-machine. Now, assuming that the cutting stroke is completed and the table motion reversed, we will find switch-arm 1 moved to the right. Then tracing from main 20 through the route 22 9 23 8, its only route, we find the circuit open at segment 60 8, the result being that there can be no effect derived from solenoid 4 and no feeding impulse will occur at the end of the cutting stroke. As switch-arm 1 left segment 8 it opened the general circuit, thus deenergizing solenoid 18 and permitting switch-arm 15 to fall to its lower position; but the main circuit being open at 8 the passage of switch-arm

15 over segments 16 and 17 was without effect upon solenoid 4. Under the assumed and illustrated positions for hand-switches 9 and 12 we see that an impulse for connection 3 was an incident only to the movement of switch-arm 1 to its leftward position, the movement of that switch-arm to the rightward position being without effect. Now assume hand-switch 9 to be shifted to contact 11. We then see that any circuit dependent on segment 8 will be open at contact 10, the consequence being that no current can go to the parts as an incident to switch-arm 1 being in its leftward position. The feeding impulse will therefore not be given to the planer as it begins its cutting stroke; but as the cutting stroke ends and the table motion reverses, we will find switch-arm 1 to the right and engaging segment 7. We now trace from main 20 through route 22, 9, 11, 24, 7, 1, 6, 25, 26, 18, and 27 to main 21 and find solenoid 18 energized, the result being that switch-arm 15 goes up, as in the former case, and causes the temporary energization of solenoid 4 and the giving of an excursion to connection 3. Therefore when hand-switch 9 is to contact 10 an impulse will be given to connection 3 only when connection 2 goes to the left, and when 95 the hand-switch is put to contact 11 an impulse will be given to connection 3 only when connection 2 goes to the right. Hand-switch 9 therefore serves in making a selection from two conditions or positions, of one condition or position under which an impulse shall occur at connection 3. Now with all other parts in the position indicated in Fig. 1, assume hand-switch 12 to be put to contact 14. We trace from main 20 through route 14, 22, 9, 10, 23, 8, 1, 6, 25, 26, 18, and 27 to main 21 and find solenoid 18 energized, the result being the upward movement of switch-arm 15 and the energization of solenoid 4 and an excursion for connection 3. An impulse for 110 connection 3 thus becomes an incident to the leftward location of switch-arm 1. The energizing-circuit through solenoid 4 will have a somewhat different route than in the previous cases, for it will be from 29 through 12 115 and 14 to main 20 instead of through 13 25, &c. Thus when hand-switch 12 is at contact 14 we find an impulse for connection 3, resulting from the leftward position of connection 2. When hand-switch 12 being on contact 14 switch-arm 1 goes to the right, we trace from line 20 through any route and find no current through solenoid 18; but while switch-arm 1 was at the left the solenoid was energized through a route which we have 120 heretofore traced, and when that switch-arm moved to the right off of segment 8 it opened the circuit-energizing solenoid 18, thus permitting switch-arm 15 to fall and sweep segments 16 and 17 and bring about the energization of solenoid 4 through a direct route including 12 and 14. Therefore when hand-switch 12 is at contact 14 an impulse will be given to connection 3 as an incident to either

the rightward or leftward movement of connection 2. Briefly, then, hand-switch 12 determines whether connection 3 shall receive an impulse as an incident to both movements of connection 2 or only one of its movements, and hand-switch 9 determines at which of the two movements the impulse shall occur in the latter case. The tracing of the circuits will show that when hand-switch 12 is to contact 14 to bring about the double impulse it is immaterial whether hand-switch 9 be on contact 10 or contact 11, so long as it is on one of them.

Fig. 2 illustrates a practical embodiment of the system in the form of a self-contained apparatus whose features of construction will be obvious from the drawings, it being only necessary to state that the hand-switches 9 and 12 are here illustrated as of the jackknife type and that, in addition to the parts which have been heretofore considered, 31 indicates the foundation-slab for the parts; 32, the binding-posts for various connections; 33, insulated prolongations of the contact-segments to produce continuous surfaces for the switch-arms, and 34 the jacket-housings of the solenoids.

I claim as my invention—

1. In an electric switch system, the combination, substantially as set forth, of a normally open first circuit, a translating device included therein, a first switch for temporarily closing said open circuit, a second circuit, a second translating device included in said second circuit, mechanism operatively connecting the second translating device with said first switch, a second switch disposed in the second circuit and having alternative con-

tacts of closure, a first hand-switch and a second hand-switch, each having alternative contacts of closure, and electrical connections between said hand-switches and circuits, whereby one position of the first hand-switch results in the first translating device being energized only under one selected condition of said second switch and whereby another position of the first hand-switch results in the first translating device being energized only under another selected condition of said second switch, and whereby the shifting of the second switch causes the first translating device to be energized under a plurality of conditions of said second switch, substantially as set forth.

2. In an electric switch system, the combination of a first circuit, a first solenoid and core included therein, a mechanical connection from said core to transmit an effect therefrom, a normally open first switch in said first circuit, a second solenoid having a core connected with said first switch for operating it, a second circuit connected with said first switch and second solenoid, a second switch connected with both said circuits, a mechanical connection to serve in giving operative movements to said second switch, a hand-switch connected with said first circuit and second switch, and a hand-switch connected with the first circuit and second circuit, arranged and operating substantially as set forth.

ADOLPH L. DE LEEUW.
